UNITED STATES PATENT OFFICE

LEE E. ALLEN, OF NEW CASTLE, PENNSYLVANIA, ASSIGNOR TO PENNSYLVANIA ENGINEERING WORKS, OF NEW CASTLE, PENNSYLVANIA, A CORPORATION OF PENNSYLVANIA

MANUFACTURE OF DUMP CARS

Application filed January 2, 1929. Serial No. 329,722.

This invention relates generally to dump cars and more particularly to dump cars of the type particularly adapted for transporting slag from a furnace to a dump pit.

5 In the accompanying drawings which illustrate the present preferred embodiment of my invention, the drawings being given by way of illustration only and not by way of limiting the invention thereto,

10 Figure 1 is a partial side elevation of a slag car embodying my invention;

Figure 2 is a plan view of the device shown in Figure 1;

Figure 3 is an end elevation of the slag car 15 showing the various positions the pot takes in the dumping operation;

Figure 4 is a partial plan view, parts being shown in section, showing the operating means for dumping the pot;

20 Figure 5 is a detail on an enlarged scale of the packing arrangement employed in the air and oil cylinders;

Figure 6 is an end elevation showing the air and oil operating cylinders, and the pipe 25 connection therefor;

Figure 7 is a partial plan view of the device shown in Figure 6, the air operating cylinders being shown only to their center line;

30 Figure 8 is an end elevation of the air and oil cylinders and the pipe connections therefor. It also shows the locking means for preventing the pot from dumping;

Figure 9 is a schematic view illustrating 35 the arrangement for operating the air and oil cylinders in order to dump the pot;

Figure 10 is a detail view of a needle valve employed in connection with the oil system in order to regulate the speed of dumping of 40 the pot;

Figure 11 shows in a somewhat diagrammatic manner the means for locking the pot so that it can not dump;

Figure 12 is a detail sectional view of the 45 means for adjusting the pot with respect to the trunnions for supporting it;

Figures 13 and 14 are detail views of a link 50 which co-operates with the trunnion of the pot and the operating mechanism in order to turn the pot;

Figure 15 is a sectional view illustrating the manner in which the pot supporting frame is connected to the bolster of the trucks in order to decrease the danger of the pot and pot frame from over-turning;

55 Figure 16 is a cross section on the line XVI—XVI of Figure 17 illustrating the bumper blocks employed in removing skulls from the slag pot; and

Figure 17 is a front elevation of the bumper block.

Referring to the drawings and particularly to Figures 1, 2 and 3, the slag pot 2 is supported by trunnions 3 mounted at their ends in end frames 4. The end frames are 60 rigidly connected together by means of the longitudinally extending center frames 5, which are riveted at their ends to the end frames as at 6. The center frames are reinforced by spreaders 7 which extend transversely of the center frames as shown in Figure 2. Forward and rear platforms 8 and 9, respectively, are connected to the end frames, and the whole frame structure is mounted on trucks 10 which are supported 65 on the usual bolster and axles carried by the wheels 11 which run on a track 12. The pot frame is provided with the usual draft gear 13, train-line 14, train-line coupling 15 and safety chains 16 which may be used in case 70 the draft gear becomes inoperative.

The trunnions 3 are formed intermediate their ends to conform to the shape of the slag pot which is supported thereby. An adjustable mounting for the pot is shown 75 in Figures 1 and 12. In accordance with this construction the trunnions 3 which intermediate their ends are formed of channel sections are arranged to co-operate with upper lugs 18 and lower lugs 19 provided on the 80 pot. The lower surfaces of the trunnions 3 are provided with ears 20 which are pivotally connected by means of pivot pins 21 to supporting blocks 22 which rest on the lower lug 19 of the pot. The trunnions are further 85 provided with bolts 23 which extend through openings formed in the trunnions and co-operate with the sides of the pot, as clearly shown in Figure 12 in order to maintain the pot in adjusted position. A lock nut 25 is 100

provided to hold the bolt 23 in adjusted position.

The upper surfaces of the end frames 4 are machined to provide a smooth bearing 5 for a track 26 on which wheels 27 secured to the ends of the trunnion may roll. The upper surfaces of the end frames 4 are also provided with racks 28 with which trunnion gears 29, secured to the ends of the trunnions, co-operate in order to dump the pot.

Means hereafter more fully described are provided for causing the trunnion gears 29 to roll along the racks 28. From the structure so far described, it will be understood 15 that when the trunnion gears 29 secured to the ends of the trunnions are caused to move in contact with the racks 28, the trunnion 3 will be caused to move along the racks 28, and at the same time to turn about the trunnion 20 as a pivot in order to cause the pot to dump. The successive positions of the pot during the dumping operation are indicated in Figure 3 by A, B and C, respectively.

The trunnion gears 29 are caused to move 25 along the rack 28 by the following mechanism. Mounted on the rear platform of the pot frame are two air cylinders 30 and two oil cylinders 31 as shown in Figure 4. Two interconnected air pistons 32 are provided to 30 move within the cylinders 30. The means for interconnecting the air pistons is clearly shown in Figure 4 and comprises a spider having arms 33 at the outer ends of which are arranged lugs 34 provided with openings 35 which receive guide rods 35, the guide rods being connected to the inner ends of the air cylinders as shown at 35' in Figure 7. The spider which connects the two air pistons 32 is further provided with a lug 36 arranged 40 on the side adjacent the pot, which co-operates with a link 37 in order to move the gear 29 along the rack 28. The link 37 is shown in detail in Figures 4, 13 and 14. It comprises a strap portion 38 which surrounds the 45 end of the trunnion 3, and a projecting lug portion 39 which co-operates with the recess provided in the lug 36 formed on the spider 33.

As the air pistons 32 are moved within the 50 air cylinder 30, the trunnion gear 29 is moved across the rack 28. Since the trunnion gear 29 is rigidly secured to the end of the trunnion 3, this causes a turning movement of the pot. By reference to Figure 4 it will be seen 55 that when the pistons 32 are in the position indicated in the figure, that is, at their extreme right hand position within the cylinders 30, the trunnion 3 is in the middle of the rack 28. When the pistons 32 are caused 60 to move to the left hand of the cylinders 30, the trunnion 3 is caused to move along the rack 28 toward the left hand of the rack and at the same time cause the pot to be dumped. However, with the link 37 in the position 65 shown in Figure 4, it is not possible to dump

the pot in the opposite direction. If it is desired to dump the pot in a clockwise direction, when looking at the end of the trunnion 3 from the end of the slag car adjacent the air cylinders, it is necessary to uncouple the link 37 from the recess in the lug 36, cause the pistons 32 to move to the left of the positions shown in Figure 4, rotate the link about the trunnion 3 and again connect it to the lug 36. In this new position of the link 37 the pot can be dumped only in a clockwise direction. This arrangement of the link 37 and the lug 36 forms a construction which allows the pot to be dumped only in one direction when the link 37 is in one position.

In order to dump the pot in the opposite direction, it is necessary to uncouple the link, rotate it about the trunnion 3 and again couple it with the lug 36. This arrangement guards against accidents because of the fact that the operator can always stand on the side of the pot opposite to that in which the pot is turned in dumping.

The oil cylinder has an oil piston 40 arranged therein, the oil piston being connected to the spider 33 so that the air pistons 32 and the oil piston 40 move in unison. As shown in the drawings, the air cylinder 30 and the oil cylinder 31 are integral with each other, but if desired they may be formed separately.

By reference to the schematic showing of Figure 9, the manner of operating the air pistons and oil pistons will be understood. With the link 37 and air pistons 32 in the position indicated in Figures 4 and 9, air is admitted into the right hand end of the air cylinder 30. This causes the air piston 32 to move from right to left as indicated in Figure 9, which movement because of the connection between the lug 36 and the link 37 causes the trunnion gear 29 to move along the rack 28 and at the same time to turn the pot in a counter-clockwise direction as viewed in Figure 4.

The air and oil pipe system is shown schematically in Figure 9 in which there is provided a main four-way air valve 41, a two-way main oil valve 42, an oil needle valve 43 and an oil by-pass valve 44. Air pipes 45 and 45' lead from the four-way main air valve 41 to the opposite ends of the air cylinders. An oil pipe 46 is connected to the opposite ends of the oil cylinders 31 through the two-way valve 42 and the needle valve 43. A pipe 47 provides a by-pass for the oil needle valve when it is desired to rock the pot in order to remove skulls therefrom. When air is admitted to the right hand end of the air cylinder 30 in order to move the air piston 32 to the left and thereby cause rotation of the pot in a counter-clockwise direction, the oil piston 40 is caused to move to the left hand because of its connection with the air-pistons. This movement of the oil piston to

the left hand causes the oil contained in the left hand oil piston 31 to discharge through the pipe 46, valve 42, and needle valve 43 and is delivered into the right hand oil cylinder 31. The needle valve 43 can be adjusted to vary the flow of oil through the valve thereby providing a cushioning means for the air pistons 32 during the ordinary dumping of the pot.

However, if it is desired to remove skulls from the inside of the pot by causing the upper edge of the pot to contact with the bumper blocks 48 shown in Figure 3, the bypass valve 44 is opened so that there is a substantially unrestricted flow of oil from one of the oil cylinders to the other, thereby causing the pot to be rapidly rotated until the pot assumes the position C shown in Figure 3, in which position the normally upper edge of the pot extends downwardly and contacts with the bumper block 48 mounted on the center frame 5. The air issuing from the left hand cylinder 30 flows through pipe 45' to the main air valve 41 and is exhausted through the exhaust pipe 49. The air for operating the air pistons is supplied from the train-line 14 shown in Figure 1.

Referring to Figures 3, 6, 7, and 8, which show the actual construction of the pipe system for actuating the pistons within their cylinders, the air supplied through the train pipe 14 flows through a main shut-off air valve 51 through a pipe 141 into the main four-way valve 41. From the main air valve 41 it passes to the right hand end of the air cylinder through the pipe 45, moving the air and oil pistons to the left as shown in Figures 6 and 7, and is exhausted from the left hand end of the air cylinders through the pipe 45', from which it flows back to the main four-way valve 41 and is exhausted through the exhaust pipe 49.

During the movement of the air piston 32 from right to left, the oil piston 40 is also caused to move from right to left. The oil in the left hand oil cylinder 31 flows through pipe 46, valve 42, needle valve 43 and returns to the right hand oil cylinder through the pipe 46'. The speed with which the oil passes through the needle valve 43 determines the dumping speed of the slag pot. In case it is desired to remove skulls from the inside of the slag pot by causing the pot to turn rapidly and be rapped against the bumper block 48, the bypass valve 44 is opened, thereby allowing the oil to flow from the left to the right oil cylinder 31, through the pipe 46, valve 42, valve 44, and into a bypass provided in the needle valve to the pipe 46', from which it is delivered to the right hand cylinder 31. It will be understood that when the valve 44 is open, the oil has an unrestricted flow from one of the oil cylinders 31 to the other. The structure of the needle valve 43 is shown in detail in Figure 10. When it is

desired to cushion the action of the air pistons 32 in the air cylinder by causing the oil to flow from one oil cylinder to the other through the needle valve 43, the oil enters the needle valve 43 through the port 46^a flowing in the direction indicated by the arrow, flows through the passage 52 controlled by the needle 53 and is delivered through the port 54 to the pipe 46'.

However, when skulls are being removed from the pot and the valve 44 is open, the oil, instead of flowing through the needle valve 43, flows through the valve 44 and is delivered into the port 54 of the needle valve through the by-pass connection 55 which communicates with the pipe 56 shown in Figure 7 and which connects the valves 44 and 43.

The main air valve 41 and the oil shut-off valve 42 which control the operation of the air and oil pistons, and therefore the turning of the pot, are operated by a man standing at one side of the slag pot. These valves are operated through the handle 57 and main shaft 58 which extends entirely across the dumping mechanism as shown in Figures 3, 6 and 8. The main shaft 58 which controls the operation of the main air valve 41 is connected by links 59, 60 and 61 (shown in Figure 8), to the oil shut-off valve 42. When the main air valve 41 is closed, the oil valve 42 likewise is closed. By this arrangement when the slag pot is in transit and no air is being used in order to dump the pot, the oil valve 42, because of its connection with air valve 41, is closed. This prevents the oil from flowing from one of the oil cylinders 31 to the other, thereby preventing the air pistons 32 from moving, and in this manner preventing any turning movement of the pot. This manner of causing the oil valve 42 to be closed when the air valve 41 is closed, therefore provides a safety means such that the pot is prevented from turning at all times except when the main air valve 41 is open.

In addition to the provision of a connection between the oil valve 42 and the air valve 41 in order to prevent the pot from turning unless the air valve is open, a second locking means is provided. This locking means is shown in Figures 8 and 11. A rod 62 extends transversely of the dump body and is of such a length that the handles 63 arranged at opposite ends thereof may be turned by a man standing on either side of the tracks supporting the dump car. The rod 62 has an eccentric portion 64 which is pivotally connected to connecting rods 65. The connecting rods are pivotally connected to a boss 66 formed on the arm 67 which is arranged to pivot at 68. The upper ends of the arms 67 have a braking block 69 secured thereto. Upon turning the handle 63 the braking block 69, through the linkage previously described, is caused to contact with or be removed from

contact with the guide rod 35 which guides the piston 32 in its movement within the air cylinder 30. The braking block 69 is of such a size that when the air piston 32 is at one end of the air cylinder, in which position the journals which support the pot will be in a position such that the pot is upright, the braking block 69 substantially fills all of the remaining space along the guide 35 which is not occupied by the collar 34 secured to the spider which connects the air pistons 32.

It will be understood that when the braking block 69 is in the position indicated in Figure 8, that is in contact with the guide rod 35, the collar on the spider is prevented from moving along the guide rod. This prevents the air cylinders from moving and therefore causes the pot to remain stationary. The present invention provides two means for preventing the pot from turning and thereby dumping out slag during transit.

In order to prevent leakage of air and oil between the air cylinder 30 and air piston 32, and between the oil cylinder and oil piston, I preferably employ the packing arrangement shown in Figure 5. An annular packing ring 70 is secured within the air cylinder 30 and is provided at its right hand end with an annular cup packing 71. The cup packing is maintained in place by an annular gland 72 secured to a shoulder 73 on the air cylinder by means of bolts 74. If air tends to leak between the cylinder and piston it causes the cup packing to expand thereby immediately closing up any opening between the cylinder and piston. Any other means than the cup packing may be employed to prevent leakage between the cylinder and piston. For example, the usual piston and piston ring arrangement may be employed if desired.

One characteristic of slag cars heretofore known is that because of the relatively high center of gravity of the structure, there is possibility of tipping over the slag pot.

My invention provides a slag car in which the center of gravity is relatively low as compared with those previously known. The operating cylinders are below the center line of the trunnion gears 29 used in tipping the pot. I further provide against accidental tipping of the car body by securing the car body to the trucks on which the body is supported. One means for securing the car body to the trucks is illustrated in Figure 15 in which the car body 75 and the bolster 76 are connected by a king pin 77 extending through the car body and bolster and held in place by a key 78 and cotter pin 79. The bolster and car body are provided with cooperating recesses and projections 80 and 81 in order to provide a secure seat for the body on the bolster. By this arrangement the car body and the trucks are secured to each other, thereby rendering it much more

difficult to tip over the car body than if it were possible to tip the car body without tipping the trucks.

I have illustrated and described the present preferred embodiment of my invention. It is to be understood, however, that the invention may be otherwise embodied without departing from the spirit of my invention or the scope of the following claims.

I claim:

1. A dump car comprising a pot supported by a trunnion having a trunnion gear and rack associated therewith, an air cylinder and piston and an oil cylinder and piston, a source of air supply for operating said air piston, means connecting said gear and pistons, a pipe connecting opposite ends of the oil cylinder, a valve arranged in said pipe for regulating the speed of dumping the pot, and means for by-passing the oil from one end of the oil cylinders to the other around said valve, thereby enabling the pot to be rapidly rotated and bumped in order to remove skulls.

2. A dump car comprising a pot supported by a trunnion having a trunnion gear and rack associated therewith, an air cylinder and piston and an oil cylinder and piston, a source of air supply for operating said air piston, means connecting said gear and pistons, an air valve for controlling said air piston, a pipe connecting opposite ends of the oil cylinder, an oil valve arranged in said pipe for regulating the speed of dumping the pot, and means for preventing passage of oil to the opposite end of the oil cylinder when said air valve is closed.

3. A dump car comprising a pot supported by a trunnion having a trunnion gear and rack associated therewith, an air cylinder and piston and an oil cylinder and piston, a source of air supply for operating said air piston, means connecting said gear and pistons, an air valve for controlling said air piston, a pipe connecting opposite ends of the oil cylinder, an oil valve arranged in said pipe for regulating the speed of dumping the pot, said air and oil valves being operably connected so that when the air valve is closed oil cannot pass from one end of the oil cylinder to the other, thereby preventing the pot from turning.

4. A dump car comprising a pot supported by a trunnion having a trunnion gear and rack associated therewith, a plurality of air cylinders having interconnected pistons for moving said gear along said track to turn the pot, and a reversible link connection between said pistons and trunnion, the link being rotatable about the trunnion and shiftable laterally therewith while maintaining a fixed angular position.

5. A dump car comprising a pot supported by a trunnion having a trunnion gear and rack associated therewith, a plurality of air

cylinders having interconnected pistons for operating said gear to turn the pot, a reversible link for connecting the pistons and trunnion having a collar portion surrounding the trunnion in which the trunnion can freely rotate, the link exerting a force on the trunnion in a direction substantially parallel to the longitudinal axis of the air cylinders.

10 6. In a dump car having a pot adapted to be tipped by a piston reciprocating in an air cylinder, the piston having a collar slideable along a guide rod, a braking mechanism comprising a braking block movable into co-operative relation with the guide rod to prevent movement of the piston, an actuating rod having an eccentric portion, and a link connected to the eccentric portion for actuating the braking block.

20 7. In a dumping car having lugs adapted to receive a trunnion for supporting the pot, a centering and clamping device for the pot comprising a block pivotally connected to the trunnion and contacting with one of the 25 lugs, and means for moving the pot relative to the trunnion.

8. In a dumping car having upper and lower lugs adapted to receive a channel shaped trunnion for supporting the pot, a 30 centering and clamping device for the pot comprising a block pivotally connected to the trunnion adjacent its lower edge and contacting with the lower lugs, and means for moving the pot relative to the trunnion.

35 9. In a dumping car having upper and lower lugs adapted to receive a channel shaped trunnion for supporting the pot, a centering and clamping device for the pot comprising a block pivotally connected to the trunnion adjacent its lower edge and 40 contacting with the lower lugs, the upper edge of the trunnion being in contact with the upper lugs, and a screw extending through the trunnion and in contact with the 45 side of the pot for moving the pot relative to the trunnion.

In testimony whereof I have hereunto set my hand.

LEE E. ALLEN.
